Antti, Chase and North, of Philadelphia Penn.

Letters Patent No 1795 dated June 30th 1863.

The schedule referred to in these Letters Patent and making part of the same

Is as follows, to wit:

Be it known that we, Garrettson Smith and Henry Brown, of the firm of Smith and Brown, of the City of Philadelphia, in the state of Pennsylvania, have invented or produced a new and original "Design for the Plates of a Fire board Stove;" and we do hereby declare that the following is a full, and exact description thereof, reference being had to the accompanying drawings, making a part of this specification.

Des. 1795

in which figure 1. is a sectional view of the hearth plate.

Figure 2. the front plate of the ash box.

Figure 3. one of the two side plates of the said ash box.

Figure 4. the cap plate of the stove, and

Figures 5 and 6. the top plate of the ash box.

The hearth plate (figure 1) has a plain flat surface which is bounded at its side and front edges by the fingered or ornamental moulding a. a, as represented in the drawing, figure 1.

The front plate of the ash box (fig. 2.) has an opening through it for access to the ash pan as usual, and is ornamented at each end by a scroll leaf b. of the configuration shown in the drawing, fig 2.

The side plates of the ash box (figure 3) are each ornamented at the front end by a scroll leaf c. of the configuration shown in the drawing figure 3.

The cap plate (figure 4.) has its exposed half ornamented by a fingered edge c, inclosing a raised surface ornamented by a series of raised and depressed figures d. e. backed by a raised ornamental moulding f. all of the configuration shown in the drawing.

The top plate of the ash box (figures 5 and 6.) has its exposed half ornamented by the corner figures g. g. and the double fringe h. h. around its front and side edges, as represented in the drawing figures 5 and 6.

What we claim as our invention or production, and desire to secure by letters patent is, "Design for the Plates of a Fireboard Stove" as shown and described.
